UNITED STATES PATENT OFFICE.

MORTON L. JOHNSON, OF CHICAGO, ILLINOIS, ASSIGNOR, BY MESNE ASSIGNMENTS, TO
FRANK B. COOK COMPANY, OF CHICAGO, ILLINOIS, A CORPORATION OF ILLINOIS.

TELEPHONY.

1,208,506.

Specification of Letters Patent. Patented Dec. 12, 1916.

Application filed December 4, 1912, Serial No. 734,866. Renewed May 10, 1916. Serial No. 96,717.

To all whom it may concern:

Be it known that I, MORTON L. JOHNSON, citizen of the United States, residing at Chicago, in the county of Cook and State of Illinois, have invented a certain new and useful Improvement in Telephony, of which the following is a full, clear, concise, and exact description, reference being had to the accompanying drawings, forming a part of this specification.

My invention relates to telephone exchange systems and has for its object the provision of means for associating recording devices with calling lines whose wants, for the moment, cannot be attended to by the operators owing to tension in telephonic traffic. Means are provided, when a calling line cannot be attended to at the time, for bringing a recording device into association with such calling line, there being means in association with the calling line for effecting a record upon the recording device to receive an operator's attention as soon as opportunity affords. In the preferred embodiment of the invention this recording device is in the form of a speech recording and speech reproducing mechanism upon which the calling subscriber may record what information is necessary to enable the operator to complete the connection desired and which mechanism may be set into operation by the operator when such operator is at liberty to receive the information contained thereby.

The invention is of particular service in connection with but is not to be limited to telephone exchange systems in which operators' responsive devices are automatically associated with calling lines in order to enable operators to be notified of the wants of calling subscribers.

The invention has for one object the addition to the switching mechanism employed for the purpose of an extension of its normal range of operation, in which range extension recording mechanism is to be operated by equipment of a calling line to make a record to receive an operator's attention preferably when the calls initiated within the normal range of movement of the switching mechanism have been attended to.

In the preferred embodiment of the invention the recording device is in the form of a speech recording and speech reproducing mechanism such as a phonograph or a Poul-

sen talking machine or device, preferably the latter. In the preferred embodiment of the invention one of these recording devices is provided for each operator's position but each recording device is desirably common to a plurality of switches so that the overflow load will be somewhat evenly distributed. In the preferred embodiment of the invention these overflow call recorders are each desirably capable of possible association with any telephone line entering the exchange.

My invention has other characteristics and will be fully explained by reference to the accompanying drawings showing the preferred embodiment thereof and in which—

Figure 1 is a very general diagrammatic view outlining the general plan of a system equipped in accordance with the invention; and Figs. 2, 3 and 4, taken in numerical order and with the conductors at the tops thereof in alinement, represents a telephone exchange system with its equipment shown in somewhat full detail.

Like parts in Fig. 1 and Figs. 2, 3 and 4 are indicated by similar characters of reference.

Referring first more particularly to Fig. 1, I have diagrammatically indicated two subscribers' stations at 300 and 400. Each line is here indicated as being individually provided with an electro-magnetic selective switching device A having wipers, waiting contacts and circuits whereby a line, when a calling line, may have an operator's responsive device (such as a signal lamp 1 or operator's telephone 2) associated therewith. As the invention is illustrated when a responsive device is automatically associated with a calling line such calling line is automatically extended into connection with a link connector 3 having an operator controlled terminal which may be in the form of a calling plug 4, the operator using such a plug for insertion within a jack 5 of a called line in order to complete connection between calling and called lines. The invention, however, is not to be limited to the extension of a calling line into connection with a line extending link connector simultaneously with the association of a calling line with a responsive device. Where, however, a calling line is thus automatically extended each link connector 3 is desirably associated with a re-

sponsive device (such as an electric lamp) individual thereto so that the operator will immediately know which link connector has been selected.

6 The responsive device 2 is in the form of an ordinary operator's telephone equipment, the receiver of which is capable of response to voice currents impressed upon the line at a calling station. As the system is organized, the operator will immediately be included in circuit with a calling line and will take for use the link connector 4 corresponding to the actuated signal 1, the system being so organized that but one of the signals 1 will be selectively associated with the calling line at a time, the other signals remaining inert until the signal taken for use has been excluded from circuit and the connection of the operator's telephone with the line that has caused the operation of such signal has been broken, occurrences which follow the insertion of the plug of the selected link connector into the jack of the called line, if such called line is idle, or in a busy back jack 6 if the desired line is busy. The number of signals 1 that are individual to the link connectors 4 is suited to the normal capacity of the operator and the operator's telephone 2 is common to these signals and the link connectors 4 associated therewith. If the normal capacity of the operator is exceeded the switching mechanism A will extend beyond its normal range of operation for the purpose of associating a signal device 7 with the calling line and also a recording device 8 and link connector 9, which latter element may constitute an automatically extended part of the calling line but which, as in the case of the link connectors 4, is not to be restricted to such characteristic. If the switch A is to respond to another calling subscriber before the connection initiated by the elements 7, 8 and 9 at one position has been completed, then such switch will continue further in its movement beyond its normal range to associate the additional calling line with the elements 7, 8 and 9 at another operator's position. Each of the last two waiting contacts (or sets of waiting contacts) of each switch is shown as being common to the elements 7, 8 and 9 at the different operators' positions, these positions generally indicated at B, C in Fig. 1. The recording devices 8, whether distributed among the regular operators' positions or located at special overflow positions, are preferably in the form of phonograph devices upon which the calling subscribers may indicate the connections they desire whereafter the operators, when reaching these recorders in the course of their duty, will cause the same to repeat the records impressed thereupon by the calling subscribers. I do not wish to be limited, however,

to the employment of talking devices to enable the equipment of calling lines to impress records that are later to receive operators' attention nor do I wish to be limited to the location of the recorder operating apparatus at the substations of calling lines.

I will explain my invention more in detail by reference to Figs. 2 to 4, inclusive, taken collectively and in numerical order. Each subscriber's station may be equipped with the usual apparatus comprising a telephone switch hook 10, a call bell 11, a condenser 12, a telephone receiver 13, and a telephone transmitter 14, the switch having a normal contact for including the serially related bell and condenser in bridge of the associate telephone line and an alternate contact for including the serially related telephone receiver and transmitter in bridge of the telephone line. When the receiver at a calling station is removed from its switch hook circuit is established which may be traced from the grounded battery 15 through the upper winding of a line relay 16, the upper armature switch of a switching relay 17 and its normal contact, the upper armature switch of the cutoff relay 18 and its normal contact, one side of the calling subscriber's line, the telephone bridge at the calling station, the other side of the calling subscriber's line, the lower armature switch of relay 18 and its normal contact, the intermediate armature switch of relay 17 and its normal contact, the lower coil of the relay 16, to ground. The lower armature switch of relay 16 thereupon establishes a circuit traceable from ground through this armature switch and its then engaged contact, the rotary magnet 19, the armature switch of sluggishly operating relay 20 and its contact, the winding of the relay 20, the side switch wiper 21, to the grounded battery 15. The rotary magnet 19 steps wipers 22, 23 and 24 in a rotary step by step movement until the wiper 23 engages an ungrounded contact whereupon the private magnet 25, whose circuit was established by the armature switch of the rotary magnet 19 when such rotary magnet was initially energized, has its circuit opened to move the side switch wipers 21 and 26 to their second positions, the wiper 21 in its second position opening the circuit of the rotary magnet 19 whereby the wipers 22, 23 and 24 remain at rest with the wiper 23 upon the contact which was previously ungrounded but which is now grounded by the upper armature switch of the sluggishly operating relay 27 whose circuit was previously closed at the upper armature switch of relay 16, this ground connection being completed owing to the location of the side switch wiper 26 in its second position. The ground established at the upper armature

switch of relay 27 is replaced at a later period, this ground and its substitute guarding the contact upon which the wiper 23 rests and similarly positioned contacts of other link selector switches in multiple therewith from selection by any other link selector switch.

When the side switch wiper 21 is placed in second position it establishes a circuit traceable from the grounded battery 15, through the side switch wiper 21 and its second positioned waiting contact, the switching relay 17, to the grounded upper armature switch of the sluggishly operating relay 27 by way of the contact then engaged by this switch. When the switching relay 17 is thus included in circuit sides of the calling line are extended into connection with the wipers 22 and 24 and through these wipers into connection with the talking sides of the selected link connector 3. The circuit is also established through the test circuit controlling relay 28 by way of the upper armature switch of relay 27, the relay 28 connecting the battery 15 with the thumbs of the multiple jacks 5 to prevent the calling line from being connected with another calling line. The talking sides of the selected link circuit 3 terminate in the tip and sleeve contacts of the calling plug 4.

Any usual or preferred cord circuit equipment is associated with the talking strands of the link connectors 3 and the heel strand of the plugs 4 of such link connectors and as such link connector equipment forms no part of my present invention no detailed description will be furnished thereof. There is, however, associated with such link connectors equipment in addition to the usual cord circuit equipment which will now be described: The relay 29 of a selected link connector is included in bridge of the calling line and is consequently energized, the circuit for the signal device 1 individual to the selected link connector being closed at the upper armature switch of the relay 29. The intermediate armature switches of the energized relay 29 pertaining to the selected link connector established a bridge between the sides of the selected link connector, which bridge includes a condenser 30, a secondary coil 31, and an operator's receiver 2 at one position and common to the link connectors at that position.

The operator's local transmitter circuit is illustrated at 32 and has the usual primary 33 in inductive relation with the secondary 31. By this arrangement the automatically selected operator's telephone equipment is in telephonic relation with the calling line so that the calling subscriber and the automatically selected operator may converse. The operator having learned the connection desired inserts the calling plug 4, which is individual to the signal 1, in the jack 5 of

the desired line, assuming that the line has tested idle, or in the busy back jack 6 if the wanted line has tested busy.

In order to prevent an additional calling subscriber from selecting an operator's telephone while in selected condition I provide a relay 34 at each operator's position common to the group of link connectors thereat whose circuit is established at the lowermost armature switch of relay 29 and which relay 34 is provided with as many armature switches as there are link connectors in the group having the relay 34. Each of these armature switches is grounded and is provided with a contact each individual to a different link connector. These contacts are connected with the waiting contacts pertaining to the wipers 23 in the different link selector switches A by way of the lowermost switch of the sluggishly operating relay 35, each link connector having such a relay 35. When the calling plug 4 is inserted in the jack 5, or the jack 6, a circuit, which is apparent, is established through the corresponding relay 35, whereupon the circuit for the relay 29 is opened at the two upper armature switches of the relay 35 causing the signal device 1 pertaining to the selected link connector to be excluded from circuit and to exclude the operator's telephone from bridge connection with the calling line. At the same time circuit for the common relay 34 is opened where it was previously closed at the bottom armature switch of the relay 29. When the relay 34 is deenergized its armature switches are released so that the various contacts thereof are ungrounded whereby the contacts for the wipers 23 corresponding to all such ungrounded contacts excepting the one individual to the selected link connector, are ungrounded, the contact corresponding to the selected link connector having previously been grounded at the lower armature switch of the calling supervisory relay 36. Another link connector in the same group with the link connector whose plug 4 has been inserted in a jack 5, is now subject to automatic selection by another calling line. If the plug 4 has been inserted in some jack 5 the operator will take down the connection when the usual supervisory signals are displayed at the calling subscriber's supervisory signal 37 and the called subscriber's supervisory signal 38. If the plug 4 has been inserted in the jack 6 the circuit of the supervisory signal 38 is intermittently opened owing to the interrupter 39 and the operator will take down the connection when the signal is displayed at 37. When the plug was inserted in its jack circuit for the relay 40 was established, the lowest armature switch of this relay establishing a circuit traceable from ground through this armature switch and its contact to the corresponding waiting contact 130

pertaining to the wiper 23 whereby the ground at the upper armature switch of relay 27 is further replaced, the ground at the bottom armature switch of the relay 40 being the only ground that remains upon the corresponding waiting contact of the wiper 23 when the subscribers have replaced their telephones upon their switch hooks. When the plug 4 is withdrawn from its engaging jack the ground at the bottom armature switch of relay 40 is removed to open the circuit of the switching relay 17. The bottom armature switch of relay 17 thereupon establishes circuit through the associate release magnet 41 and the previously closed off normal switch 42 whereby the wipers 21, 22, 23, 24 and 26 are restored to normal.

The relay 35 is made sluggish in action to prevent ground from being placed upon the contact buttons of the different switches individual to the selected link connector in the event of relay 34 having been operated by another relay 29 consequent upon the initiation of another call by way of another link connector in the same group. The link connector previously selected and included in connection with the jack 5 or jack 6 is now subject to reselection upon the initiation of another call whether by the same calling line or another calling line. If all of the responsive devices 2 at the different positions are in selected condition and further calls are being initiated the switches A pertaining to the additional calling lines will continue beyond their normal ranges of movement to associate the calling lines with the signal devices 7 and 8 and, as the invention is illustrated, each additional calling line is extended into connection with a link connector having a calling plug 9, a result which is accomplished when the wiper 23 encounters an ungrounded contact button beyond the normal range of the wiper 23. This button is guarded against selection by other link selector switches as previously described and further description of this feature need not be furnished. The relay 29 having been energized upon the selection of an extra link connector having a plug 9, the associate magnet 34 is energized to attract its armature switch (or switches each individual to an extra link connector if there be a plurality of such). The lower armature switch of the relay 29 now establishes a circuit for the associate relay 34 which operates to guard the selection of a selected recording device 8 while in selected condition, as in a manner previously described in connection with the similar relay 34 in its guarding relation to the telephone 2. The lower armature switch of relay 29 also establishes a circuit for the relay 43. The right hand armature switch of relay 43 establishes a circuit traceable from the ground connected with this switch through

the contact of this switch, the right hand armature switch and contact of the relay 44, the motor 45, and the grounded battery 15. The motor 45 causes the steel tape 46 to travel in the direction indicated by the arrow, this steel tape being caused to travel throughout the distance of its entire length, the disk 47, also driven by the motor 45 serving, when the cycle of movement of the tape 46 has been concluded, to bring an insulating portion of its periphery into engagement with the brush 48 whereby a circuit for the battery 15 and motor 45 is opened, this circuit having previously included, when the disk had moved from its idle position, this motor in such circuit by way of the brush 48 and the metallic portion of the disk then engaged thereby.

Before the brush 48 engages the insulating portion of the disk 47 the finger 49 closes the switch 50 momentarily thereby to close the circuit of magnet 44 for the purpose of opening the circuit previously established through the motor 45 so that this motor is brought to rest. The relay 44, when energized, establishes a locking circuit for itself traceable from the grounded battery 15 through the winding of relay 44, the left hand armature switch of this relay 44, to the left hand grounded armature switch of relay 43 by way of the contact of this switch so that the circuit of the motor 45 is maintained open until the relay 43 is de-energized at a later period.

The steel tape 46 passes between the poles presented by the soft cores of the recording magnet 51, the reproducing magnet 52, and the record erasing magnet 53. The recording magnet is included in a secondary or induced circuit that is closed by the right hand armature switch of the relay 54 when this relay is energized upon the closure of its circuit at the left hand armature switch of relay 43. The erasing magnet 53 is included in a closed local circuit with the battery 55 at the intermediate armature switch of relay 54 when energized. The primary circuit pertaining to the recording magnet 51 is closed at the left hand armature switch of relay 54 when energized. This primary circuit includes a bridge that is established across the sides of the selected link connector extending to the plug 9 and contains the calling subscriber's telephone equipment. This bridge includes the primary coil 56 in inductive relation with the secondary coil 57 in the secondary circuit that includes the recording magnet 51. The calling subscriber merely speaks the number of the desired line, the voice currents which the calling subscriber then impressed upon his line being transmitted at 56 and 57 so that they are impressed upon the recording magnet 51, this magnet in turn effecting a record upon the tape 46. When the

finger 49 momentarily closes the switch 50 a circuit is established that includes this switch, the relay 61 and the grounded battery 15.

5 A locking circuit is established for the relay 61 by way of the left hand grounded armature switch of relay 43, left hand armature switch and its contact of relay 44. The left hand armature switch of the relay 61 thereupon closes the circuit for the signal 7 individual to the link connector that pertains to the selected recorder 8 that may be common to a number of the extra link connectors having the connecting plugs 9. When 10 the operator is able to respond to the signal 7 she depresses her key 62 to include her telephone set in a closed local secondary circuit that contains the secondary coil 63, the primary for which resides in the 15 coil 64 included in the circuit with the reproducing magnet 52. When the key 62 is depressed the relay 65 is included in circuit, the right hand armature switch of the relay 65 operating to start the motor 45 which 20 continues throughout the cycle controlled, as before, by the disk 47, whereby the tape 46 is caused to pass through its range of travel again so that the magnetic fields upon the tape at 51 operate to induce corresponding 25 fields upon the magnet 52 to cause voice currents in the local circuit that includes the primary 64, this local circuit having been closed at the left hand armature switch of relay 65. The magnet 52, like magnets 51 30 and 53, has soft iron cores upon which account magnet 52 is included in circuit with the battery 66.

When the recording fields upon the tape 46 are being passed into co-operation with the 40 reproducing magnet 52 the circuit for the erasing magnet 53 is opened at the right hand armature switch of the energized relay 61. When the key 62 is depressed its lowermost contacts close circuit through the 45 relay 34 associated with the link connectors 3 to prevent any such link connectors from being selected while the operator is listening to the record of the recording device 8. The operator having heard the record, will complete the connection as noted upon the record by inserting the calling plug 9 of the 50 selected link connector into the jack of the desired line if idle, or if the line is busy by inserting such plug into the busy back jack 55 6. In either of which cases the relay 29 is de-energized, the lowermost armature switch of this relay opening the circuits of relays 34, 43 (Fig. 4) which in turn opens the circuit of relays 44 and 54 whereby the equipment is restored to normal. When a new call is initiated 60 the magnet 53 operates to erase the previous record and to prepare the tape 46 for the reception of a new record. When the key 62 is operated a circuit is closed for operating 65 relay 67 to open the circuit of the recording

magnet 51 and to close the circuit of a tone device 68 which includes a winding 69 in inductive relation to the winding 56, whereby the tone transmitted to the calling subscriber indicates the operator has responded. There 70 is also provided a tone device 70 which transmits a tone to the calling subscriber while the wipers 22, 23 and 24 are traveling whereby the calling subscriber can ascertain when an idle responsive device has been selected. 75 The absence of the tone indicates that the wants of the subscriber can be expressed without waiting for a reply from the operator. The link connectors illustrated at 4, 4, 9 at the bottom of Fig. 4 indicate another 80 operator's position C.

In other applications I have shown means whereby calling subscribers may record information upon phonographic receivers to enable operators to receive such information 85 for the purpose of establishing connections, the claims in my present application relating specifically to an overflow system, claims of other scope being contained in other applications. 90

While I have herein shown and particularly described the preferred embodiment of the invention I do not wish to be limited to the precise details of construction and circuit arrangement shown as changes may 95 readily be made without departing from the spirit of the invention, but

Having thus described my invention I claim as new and desire to secure by Letters Patent the following:—

1. A telephone exchange system including telephone lines extending from substations to an exchange; link connectors controlled at an operator's position for effecting connection between telephone lines; an additional link connector controlled at the aforesaid position for effecting connection between telephone lines; and speech recording and reproducing mechanism adapted to be associated with calling lines by equipment 105 of said additional link connector and operable by telephonic current impressed at a calling station upon the calling telephone line to record the calling subscriber's speech 110 and operable to convey the recorded speech 115 to the operator at said position.

2. A telephone exchange system including telephone lines extending from substations to an exchange; link connectors controlled at an operator's position for effecting connection between telephone lines; speech recording and reproducing mechanism; and a connector having equipment for associating this mechanism with a calling line, said mechanism being operable by telephonic current impressed at a calling station upon the calling telephone line to record the calling subscriber's speech and operable to convey the recorded speech to the operator at said position. 120 125 130

3. A telephone exchange system including telephone lines extending from substations to an exchange; link connectors controlled at an operator's position for effecting connection between telephone lines; automatically operating switching mechanism for connecting these link connectors with calling line; and speech recording and reproducing mechanism adapted to be 10 associated with calling lines by said additional link connector and operable by telephonic current impressed at a calling station upon the calling telephone line to record the calling subscriber's speech and operable to convey the recorded speech to the operator at said position.
4. A telephone exchange system including telephone lines extending from substations to an exchange; link connectors controlled 20 at an operator's position for effecting connection between telephone lines; speech recording and reproducing mechanism; a connector having equipment for associating this mechanism with a calling line, said mechanism being operable by telephonic current impressed at a calling station upon the calling telephone line to record the calling subscriber's speech and operable to convey the recorded speech to the operator at 30 said position; and automatically operating switching mechanism for connecting said connectors with calling lines.
5. A telephone exchange system including telephone lines extending from substations 35 to an exchange where operators' responsive devices are located; link connectors controlled at an operator's position for effecting connection between telephone lines; operator responsive device selector switches for associating operator responsive devices free for selection with calling lines throughout the 40 normal range of operation of such selector switches; and recording devices adapted to be associated with calling lines by selector switches when operated beyond their normal 45 ranges of operation.
6. A telephone exchange system including telephone lines extending from substations to an exchange where operators' responsive 50 devices are located; link connectors controlled at an operator's position for effecting connection between telephone lines; operator responsive device selector switches for associating operator responsive devices free for 55 selection with calling lines throughout the normal range of operation of such selector switches; and speech recording and reproducing mechanism adapted to be associated with calling lines by the selector switches 60 when operating beyond their normal ranges of operation and operable by telephonic current impressed at a calling station upon the calling telephone line to record the calling subscriber's speech and operable to convey 65 the recorded speech to an attendant operator.
7. A telephone exchange system including telephone lines extending from substations to an exchange; link connectors controlled at an operator's position for effecting connection between telephone lines; an additional 70 link connector controlled at the aforesaid position for effecting connection between telephone lines; speech recording and reproducing mechanism adapted to be associated with calling lines by equipment of said additional 75 link connector and including a recording magnet operable by telephonic current impressed at a calling station upon the calling line; a reproducing magnet adapted for telephonic relation with the operator's telephone; and a recording element operated upon by the recording magnet and operating upon the reproducing magnet.
8. A telephone exchange system including telephone lines extending from substations 80 to an exchange; link connectors controlled at an operator's position for effecting connection between telephone lines; speech recording and reproducing mechanism; a connector having equipment for associating this 85 mechanism with a calling line, said mechanism including a recording magnet operable by telephonic current impressed at a calling station upon the calling line; a reproducing magnet adapted for telephonic relation with the operator's telephone; and a recording element operated upon by the recording magnet and operating upon the reproducing magnet.
9. A telephone exchange system including 90 telephone lines extending from substations to an exchange; link connectors controlled at an operator's position for effecting connection between telephone lines; automatically operating switching mechanism for 95 connecting these link connectors with calling lines; an additional link connector; speech recording and reproducing mechanism adapted to be associated with calling lines by said additional link connector and including a recording magnet operable by telephonic current impressed at a calling station upon the calling line; a reproducing magnet adapted for telephonic relation with the operator's telephone; and a recording element operated upon by the recording magnet and operating upon the reproducing magnet.
10. A telephone exchange system including 100 telephone lines extending from substations to an exchange; link connectors controlled at an operator's position for effecting connection between telephone lines; automatically operating switching mechanism for 105 connecting these link connectors with calling lines; an additional link connector; speech recording and reproducing mechanism adapted to be associated with calling lines by said additional link connector and including a recording magnet operable by telephonic current impressed at a calling station upon the calling line; a reproducing magnet adapted for telephonic relation with the operator's telephone; and a recording element 110 operated upon by the recording magnet and operating upon the reproducing magnet.
11. A telephone exchange system including 115 telephone lines extending from substations to an exchange; link connectors controlled at an operator's position for effecting connection between telephone lines; speech recording and reproducing mechanism; a connector having equipment for associating this mechanism with a calling line, said mechanism including a recording magnet operable by telephonic current impressed at a calling station upon the calling line; a reproducing magnet adapted for telephonic relation with the operator's telephone; and a recording ele- 120
- 125
- 130

ment operated upon by the recording magnet and operating upon the reproducing magnet; and automatically operating switching mechanism for connecting said link connectors with calling lines.

11. A telephone exchange system including telephone lines extending from substations to an exchange where operators' responsive devices are located; link connectors connected at an operator's position for effecting connection between telephone lines; operator responsive device selector switches for associating operator responsive devices free for selection with calling lines throughout the normal range of operation of such selector switches; speech recording and reproducing mechanism adapted to be associated with calling lines by the selector switches when

operating beyond their normal ranges of operation and including a recording magnet 20 operable by telephonic current impressed at a calling station upon the calling line; a reproducing magnet provided with equipment for effecting telephonic relation with the operator's telephone; and a recording element operated upon by the recording magnet and operating upon the reproducing magnet.

In witness whereof, I hereunto subscribe my name this twenty-seventh day of November A. D., 1912.

MORTON L. JOHNSON.
